(57) **CLAIM**

(**) Term: **14 Years**

The ornamental design for a manual leveling rotating laser with swivel head, as shown and described.

(21) Appl. No.: **29/156,470**

DESCRIPTION

(22) Filed: **Mar. 1, 2002**

FIG. 1 is a perspective view of a first embodiment of a manual leveling rotating laser with swivel head, showing our design, in a first position;

(51) LOC (7) Cl. **10-04**

FIG. 2 is a right-side elevational view of the embodiment of FIG. 1;

(52) U.S. Cl. **D10/69**

FIG. 3 is a left-side elevational view, showing the side opposite that in FIG. 2;

(58) Field of Search ..... D10/69, 114; 33/286, 33/290-295, DIG. 21, 263, 279; 340/468, 472; 353/28, 121, 122; 364/468.01, 468.21, 468.25; 395/125, 201-204; 378/204-207

FIG. 4 is a front elevational view of the embodiment of FIG. 1;

(56) **References Cited**

FIG. 5 is a rear elevational view, showing the side opposite that in FIG. 4;
